(57) **CLAIM**

The ornamental design for a covered slide, as shown and described.

DESCRIPTION

FIG. 1 is a perspective view of the covered slide according to a first embodiment;

FIG. 2 is a left side elevation view of the covered slide of FIG. 1;

FIG. 3 is a right side elevation view of the covered slide of FIG. 1;

FIG. 4 is a top plan view of the covered slide of FIG. 1;

FIG. 5 is a bottom plan view of the covered slide of FIG. 1;

FIG. 6 is a front elevation view of the covered slide of FIG. 1;

FIG. 7 is a back elevation view of the covered slide of FIG. 1;

FIG. 8 is a perspective view of the covered slide according to a second embodiment;

FIG. 9 is a left side elevation view of the covered slide of FIG. 8;

FIG. 10 is a right side elevation view of the covered slide of FIG. 8;

FIG. 11 is a top plan view of the covered slide of FIG. 8;

FIG. 12 is a bottom plan view of the covered slide of FIG. 8;

FIG. 13 is a front elevation view of the covered slide of FIG. 8; and,

FIG. 14 is a back elevation view of the covered slide of FIG. 8.

The broken lines in the figures represent environment and form no part of the claimed design. The covered slide is shown with symbolic breaks in its length. The appearance of

(Continued)

any portion of the article between the break lines forms no part of the claimed design. Cover sections are repeated at regular intervals on a downward sloping portion of the covered slide.

1 Claim, 10 Drawing Sheets
